UNITED STATES PATENT OFFICE.

THOMAS J. NEACY, OF MILWAUKEE, WISCONSIN.

SPROCKET-WHEEL.

SPECIFICATION forming part of Letters Patent No. 516,550, dated March 13, 1894.

Application filed November 25, 1891. Serial No. 413,070. (No model.)

To all whom it may concern:

Be it known that I, THOMAS J. NEACY, of Milwaukee, in the county of Milwaukee and State of Wisconsin, have invented certain

5 new and useful Improvements in Sprocket-Wheels; and I do hereby declare that the following is a full, clear, and exact description of the invention, which will enable others skilled in the art to which it pertains to make 10 and use the same, reference being had to the accompanying drawing, and to the letters of reference marked thereon, which form a part of this specification.

15 My invention relates to improvements in a sprocket wheel of the type shown in United States Letters Patent No. 457,420, granted to me August 11, 1891.

Its main object is to prevent the chain from running upon the ears which are intended to 20 guide it upon the sprockets.

It consists essentially of forming or providing the ears opposite the sprockets with lateral projections by which the conveyer chain, in case it is carried to one side, is prevented 25 from engaging with said ears, and is guided back between said ears into its proper position upon the sprockets.

The accompanying drawing shows in a perspective view a sprocket wheel provided with 30 my improvement.

I have found by experience that the guiding ears placed opposite the sprockets and constructed as shown and described in my former patent above referred to, while generally effecting the purpose for which they were designed, sometimes engage with the links of the chain when it is deflected to one side of its proper course, and the wheel or its connections is thus broken or otherwise injured or 35 displaced. To avoid this difficulty and to carry the conveyer chain back to its proper position upon the sprockets in case it is accidentally deflected to one side so as to cause the links to run upon the ends of the guiding 40 ears, I form or provide said ears at or near their ends with lateral projections, which are inclined inwardly toward the interposed sprockets.

Referring to the drawing, A represents a

sprocket wheel of the same general construction as that shown in my former patent, and provided in like manner with sprockets B B, and at each side thereof with ears C, which project radially beyond the sprockets. Clear open spaces for alternate links of the chain 55 are left between the sprockets and the associated ears. Upon their outer faces and at or near their outer ends, I form or provide these ears with lateral projections c, which are inclined from their outer extremities c' 60 inwardly to the ends of said ears, so that in case the conveyer chain is deflected and carried thereon, the links will be prevented from passing over and engaging with the ears C, and will be guided back into proper position 65 upon the sprockets B. These lateral projections may be cast in the shape of wings integrally with the ears C, or may be made separate and attached thereto. They may also be variously modified as to form without materially affecting their mode of operation.

I claim—

1. A sprocket wheel provided on each side of and opposite the sprockets with ears having lateral guiding projections at their ends, 75 substantially as and for the purposes set forth.

2. A sprocket wheel provided on each side of and directly opposite the sprockets with ears having lateral projections at their outer ends inclined inwardly toward the sprockets, 80 substantially as and for the purposes set forth.

3. A sprocket wheel provided on each side of and directly opposite the sprockets, with ears extending radially beyond the sprockets and having lateral projections at their outer 85 ends inclined inwardly toward the sprockets, so as to guide and retain the chain thereon, said sprocket wheel having clear open spaces between the sprockets and the associated ears for alternate links of the chain, substantially 90 as and for the purposes set forth.

In testimony that I claim the foregoing as my own I affix my signature in presence of two witnesses.

THOMAS J. NEACY.
